UNITED STATES PATENT OFFICE

ALOIS F. MELCSOK, OF NEW YORK, N. Y.

RAILROAD COLLISION SAFETY DEVICE

Application filed October 24, 1930. Serial No. 490,838.

This invention relates to new and useful improvements in a railroad collision safety device.

The invention has for an object the provision of a railroad collision safety device which will signal each time that a train passes a control point on a track section to indicate this fact to the engineer of the train even though a galvanometer be also used with the safety device for measuring the resistance of the track section to ascertain the distance which another train is away from the first train so that when there is no second train on the track a small current can be used so that the galvanometer reads zero. The engineer of the train can at all times check up whether his instruments are working properly, and only when a second train is on the track should the galvanometer operate.

Another object of this invention is to provide a galvanometer connected in a circuit on a train for measuring the electrical resistance of the track section to ascertain the distance at which another train is upon the same track.

A further object of this invention is the provision of a means for warning either by a warning lamp or by an audible signal in the event that the train approaches too closely another train upon the same tracks.

This invention has for a still further object the provision of a device of the class mentioned which is of simple durable construction, dependable in use and efficient in action, and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:-

Fig. 1 is a plan view of a track with train trucks on the track and a schematic showing of the safety device.

Fig. 2 is a fragmentary enlarged detailed view of a portion of the track, a trip shoe

which is carried by the train, and a control adjacent the track section.

Fig. 3 is a fragmentary enlarged detailed view of a portion of one rail of the track showing the insulation between the track sections.

Fig. 4 is a transverse sectional view of Fig. 3, showing particularly the insulation material.

Fig. 5 is a side elevational view of the control element which is placed on the track road, per se.

Fig. 6 is an end elevational view of Fig. 5.

Fig. 7 is a view similar to Fig. 5, but showing the casing of the control element removed.

Fig. 8 is a fragmentary side elevational view similar to Fig. 6, but showing the casing completely removed.

Fig. 9 is a sectional view taken on the line 9—9 of Fig. 8.

Fig. 10 is an elevational view of the spring used in the control device.

Fig. 11 is a schematic view of a track switch and the collision safety device applied.

The railroad collision safety device comprises a track section 10 electrically insulated from a previous track section 11 and from a subsequent track section 12, an arm 13 adjacent the central track section 10 and resiliently mounted for normally extending upwards and to be capable of extending downwards, a shoe 14 for mounting upon a train (only one truck 15 of the train being illustrated on the drawings) and having end contact portions 16 insulated from a central contact portion 17, an electric signal circuit for mounting on said train and including said end contact 16 and said arm 13 for signaling each time the train passes the arm 13 or

similar arms on controls along the track, another electrical signal circuit for mounting on said train and measuring electrical resistance and including said central contact 17, said arm 13, and the trucks 18 of another

train on a subsequent track section 19, and a warning circuit for mounting on said first train for operation when said second train is too close and including a portion of said

measuring circuit.

The various track sections previously referred to are all arranged upon one rail, and the other rail of the track is in complete connection so that an electrical current may run 5 along it. The electrical insulation between the track sections is accomplished by insulation strips 20 extending over the ends of the track section and brace strips 21 over the insulation strips and securely held in place 10 by bolts 22. Another insulation piece 23 is arranged between the contacting ends of the track sections. Tracks are shown mounted upon ties 24 and these held by spikes 25.

The resilient mounting of the arm 13 is 15 accomplished by a casing 26 for attachment upon the road-bed of the tracks and rotatively supporting a shaft 27 carrying a drum 28 provided with a projecting pin 29 engaging one end of an arched spring 30. The 20 other end of the arched spring is connected by a stud 31 projecting from the casing 26. In Figs. 5 and 6 the arm is shown in the vertical position, while in Fig. 2 it is shown in the downward position.

25 The shoe 14 is shown in detail in Fig. 2, and is shown to consist of a rigid straight member 32 having upwardly curved ends 33. An insulation strip 34 is attached upon the body of this member and the contacts 16 and 30 17 are secured upon the insulation strip and are insulated from each other by small pieces 35 of insulation material between the contacting ends of the contacts. Leads 36 connect with the contact 16 while a lead 37 connects with the contact 17. The shoe 14 is so mounted upon the train as to be in line with the resilient arm 13 so that as the train travels, the shoe strikes the arm and causes the arm to be lowered as before called for.

40 The electrical signal circuit for mounting upon the train and calling attention of the engineer each time the train passes one of the resilient arms 13 comprises a source of power 38 constituting a battery with one of its terminals provided with a lead 39 connecting with a branch lead 40 including a signal lamp 41 and finally terminating in the leads 36. The circuit then continues from the contacts 16 to the arm 13 which is in the vertical 45 position when first engaged by the front contact 16. For the purpose of allowing the passage of current, the arm 13 is provided with a tip contact 48 connected with lead 49 connected with an insulated contact 50 upon the said drum 28. An insulation strip 51, clearly shown in Fig. 9, serves to insulate the contact 50 from the drum. A brush 52 normally is in contact with the member 50 when the arm 13 is in the vertical and connects 55 with lead 42 which is connected with the rail section 10. The current can then pass from the section 10 through the truck 15 of the train and back along lead 43 to the other terminal of the battery 38.

60 65 The circuit for measuring the electrical

resistance of the track sections and detecting a train upon the track may be traced from the source of power or battery 38, along lead 39, then branch lead 44, through the coils 45, along lead 46 to the galvanometer 70 47. Current can then continue along lead 37 to the central contact 17 of the shoe 14. From there, it travels to the tip 48, along lead 49 to the contact 50, but now since the arm 13 is in the lowered position the contact 50 will be out of connection with the brush 52 and in connection with another brush 53 which is connected with lead 54 for electrical connection with the next section. The circuit can then continue through the truck if there is a train in this section. If not the circuit continues thru the lead 55, coming off this next section, to the brush 52 of the control of the second section. Since the arm 13 is vertical the contact 50 is in contact with the brush 52 thus allowing the circuit to continue to the lead 42 which connects to the rail. The circuit continues in this manner from rail section to rail section until it comes to a section upon which there is a train. The circuit can then continue through the truck 18, if there is a train on the track, and along the return rail 56 to the truck 15 and return lead 43 to the battery 38.

90 The galvanometer will indicate the resistance of the circuit, and the engineer will have a table which will tell him exactly how far the previous train is in the lead. In the event that the previous train is so far in the lead as to not be upon the section which is two sections to the front of the first train, then there will be little return of the current and the galvanometer will register but very slightly. It is for this purpose that the signal lamp 41 indicates each time that the train passes one of the arms 13 so that the engineer will be notified whether the galvanometer is registering to indicate a train in the lead.

100 The warning circuit for operation when the first train approaches too close upon the second train comprises a source of power which may be the same battery 38, the lead 39, the coils 45, constituting the portion of the measuring circuit before referred to. A branch lead 57 taps off from the lead 44 and connects with a trip 58 pivotally mounted and normally urged by a spring 59 against a catch 60 holding it stationarily. The catch is pivotally mounted at 61 and tensionally held in position by an adjustable spring 62. The catch 60 is in the field of operation of the coils 45 so that when current which is too strong passes through the coils, the catch 60 will move and release the trip 58 which will move under the action of spring 59 to engage against a plunger 63. The plunger 63 is normally urged outwards by a spring 64 and is in electrical connection with a lead 110

65 connected with a red warning lamp 66 or an alarm, and the circuit may then continue along lead 67 to lead 43 and back to the battery 38. Thus, when the train to the front is too close, the resistance of the measuring circuit will be correspondingly decreased and will reach a point where the current is strong enough to operate the catch 60 and the warning signal. After operation, it will be necessary to manually return the trip 58 to its original condition. This may be done by manually pressing the lead 64 of the plunger inwards so that the trip 58 is moved on its pivot and allows spring 62 to move the catch 60 to hold the trip in its set position.

In Fig. 11 the collision safety device has been shown applied to a switch on a track. The main track is indicated by reference numeral 68 and the branch track by numeral 69. The train switch for controlling the track which the train takes is indicated by reference numeral 70. One of the rails of the main track is divided into sections indicated by insulation points 71. The branch is divided also into sections by similar insulation pieces 71. An arm control 72 is arranged upon the branch track and a similar arm control 73 upon the main track, these corresponding with the controls illustrated in Fig. 5. The leads from these controls end in a two-point switch 74. The movable pole 75 of this switch is mechanically connected by a link 76 to the switch points 70 so that when the points are in one position, the circuit will be closed through one of the controls, and when in the other through the other control.

Now assume a train to be coming from the left and moving towards the right. With the train switch 70 drawn so that the train takes the branch tracks 69, the electrical switch pole 75 will close the circuit to the control 72 so that the oncoming train will be aware of any trains upon the branch section in a manner as described in detail previously. In the event that the train switch 70 is drawn so that the train takes the main track, then the pole 75 will open the circuit through the branch control 72 and close it through the main control 73 so that the train will now be capable of detecting a train to the front upon the main track.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A railroad collision safety device, comprising a track section electrically insulated

from a previous and a subsequent track section, an arm adjacent the central track section and resiliently mounted for normally extending upwards and being capable of bending downwards, a shoe for mounting on a train and having end contact portions insulated from a central contact portion, an electrical signal circuit for mounting on said train and including said end contacts and arm for signaling each time the train passes said arm and similar arms, another electrical signal circuit for mounting on said train and measuring electrical resistance and including said central contact, said arm, and the trucks of another train on a subsequent track section, and a warning circuit for mounting on said first train for operation when said second train is too close and including a portion of said measuring circuit.

2. A railroad collision safety device, comprising a track section electrically insulated from a previous and a subsequent track section, an arm adjacent the central track section and resiliently mounted for normally extending upwards and being capable of bending downwards, a shoe for mounting on a train and having end contact portions insulated from a central contact portion, an electrical signal circuit for mounting on said train and including said end contacts and arm for signaling each time the train passes said arm and similar arms, another electrical signal circuit for mounting on said train and measuring electrical resistance and including said central contact, said arm, and the trucks of another train on a subsequent track section, and a warning circuit for mounting on said first train for operation when said second train is too close and including a portion of said measuring circuit, the resilient mounting of said arm being accomplished by a shaft supporting the arm and rotative in a casing, a drum on the shaft, a pin projecting from the drum, a spring connected with said pin and with a stud projecting from the casing.

3. A railroad collision safety device, comprising a track section electrically insulated from a previous and a subsequent track section, an arm adjacent the central track section and resiliently mounted for normally extending upwards and being capable of bending downwards, a shoe for mounting on a train and having end contact portions insulated from a central contact portion, an electrical signal circuit for mounting on said train and including said end contacts and arm for signaling each time the train passes said arm and similar arms, another electrical signal circuit for mounting on said train and measuring electrical resistance and including said central contact, said arm, and the trucks of another train on a subsequent track section, and a warning circuit for mounting on said first train for operation when said second train is too close and including a portion

of said measuring circuit, said electrical signal circuit for indicating each time the train passes a control arm comprising a source of current in circuit with an indicating lamp, 3 said end contacts, said arm, a lead from said arm to a contact on a drum movable upon moving of the arm, a branch contact normally in contact with the contact on the drum and connected with a lead grounded to the rail 20 section for the current to return through the trucks of the train, and a lead to the other terminal of the battery.

4. A railroad collision safety device, comprising a track section electrically insulated 15 from a previous and a subsequent track section, an arm adjacent the central track section and resiliently mounted for normally extending upwards and being capable of bending downwards, a shoe for mounting on 20 a train and having end contact portions insulated from a central contact portion, an electrical signal circuit for mounting on said train and including said end contacts and arm for signaling each time the train passes 25 said arm and similar arms, another electrical signal circuit for mounting on said train and measuring electrical resistance and including said central contact, said arm, and the trucks of another train on a subsequent track section, 30 and a warning circuit for mounting on said first train for operation when said second train is too close and including a portion of said measuring circuit, said electrical circuit for measuring the resistance when a second train is to the front of said train comprising a source of power, a galvanometer, the central contact of said shoe, the said arm, a contact connected with the arm and upon a drum so as to be movable upon rotation of the arm, a brush in contact with the latter contact in the moved or lower condition of the said arm, leads to the ground or rail connection of a track section to the front, then through the trucks of a train when upon the section to the front of said train, then along the return rail to the said battery, and comprising coils in said measuring circuit acting upon a catch holding a trip capable of closing a circuit through a warning lamp or alarm.

5. A railroad collision safety device, comprising a track section electrically insulated 70 from a previous and a subsequent track section, an arm adjacent the central track section and resiliently mounted for normally extending upwards and being capable of bending downwards, a shoe for mounting on 75 a train and having end contact portions insulated from a central contact portion, an electrical signal circuit for mounting on said train and including said end contacts and arm for signaling each time the train passes 80 said arm and similar arms, another electrical signal circuit for mounting on said train and measuring electrical resistance and including said central contact, said arm, and the trucks of another train on a subsequent track section, 85 and a warning circuit for mounting on said first train for operation when said second train is too close and including a portion of said measuring circuit, said electrical circuit for measuring the resistance when a second train is to the front of said train comprising a source of power, a galvanometer, the central contact of said shoe, the said arm, a contact connected with the arm and upon a drum so as to be movable upon rotation of the arm, a brush in contact with the latter contact in the moved or lower condition of the said arm, leads to the ground or rail connection of a track section to the front, then through the trucks of a train when upon the section to the front of said train, then along the return rail to the said battery, and comprising coils in said measuring circuit acting upon a catch holding a trip capable of closing a circuit through a warning lamp or alarm.

In testimony whereof I have affixed my signature.

ALOIS F. MELCSOK.

6. A railroad collision safety device, comprising a track section electrically insulated 90 from a previous and a subsequent track section, an arm adjacent the central track section and resiliently mounted for normally extending upwards and being capable of bending downwards, a shoe for mounting on 95 a train and having end contact portions insulated from a central contact portion, an electrical signal circuit for mounting on said train and including said end contacts and arm for signaling each time the train passes 100 said arm and similar arms, another electrical signal circuit for mounting on said train and measuring electrical resistance and including said central contact, said arm, and the trucks of another train on a subsequent track section, 105 and a warning circuit for mounting on said first train for operation when said sec- 110
